(57) **CLAIM**

The ornamental design for a protective single pocket mailing container for trading cards as shown and described.

DESCRIPTION

FIG. 1 is a perspective view of a protective single pocket mailing container for trading cards, showing my new design; FIG. 2 is a back view of my design in FIG. 1; FIG. 3 is a front view of my design in FIG. 1; FIG. 4 is a right side view of my design in FIG. 3; FIG. 5 is a left side view of my design in FIG. 3; FIG. 6 is a top view of my design in FIG. 3; FIG. 7 is a bottom view of my design in FIG. 3; FIG. 8 is a perspective view of my design in FIG. 1, shown assembled and with a sealing flap in an open position; FIG. 9 is a back view of my design in FIG. 8; FIG. 10 is a front view of my design in FIG. 8; FIG. 11 is a left side view of my design in FIG. 8; FIG. 12 is a right side view of my design in FIG. 8; FIG. 13 is a top view of my design in FIG. 8; FIG. 14 is a bottom view of my design in FIG. 8; FIG. 15 is a perspective view of my single pocket design in FIG. 8, shown assembled and with the sealing flap in a closed position;

FIG. 16 is a back view of my design in FIG. 15; FIG. 17 is a front view of my design in FIG. 15; FIG. 18 is a left side view of my design in FIG. 17; FIG. 19 is a right side view of my design in FIG. 17; FIG. 20 is a bottom view of my design in FIG. 17; and, FIG. 21 is a top view of my design in FIG. 17.

The broken lines in the drawing depict portions of the protective single pocket mailing container for trading cards that form no part of the claimed design.
